UNITED STATES PATENT OFFICE.

HARRY LANDSIEDEL, OF NORWOOD, OHIO, ASSIGNOR TO THE DALTON ADDING MACHINE COMPANY, OF CINCINNATI, OHIO, A CORPORATION OF OHIO.

RECORDING-MACHINE.

1,395,121.

Specification of Letters Patent.

Patented Oct. 25, 1921.

Application filed February 11, 1920. Serial No. 357,776.

To all whom it may concern:

Be it known that I, HARRY LANDSIEDEL, a citizen of the United States, residing at Norwood, Hamilton county, and State of Ohio, have invented a new and useful Recording-Machine, of which the following is a specification.

This invention relates to recording machines.

10 An object of the invention is to provide an improved printing mechanism for use in adding machines and in any other embodiments in which it may be satisfactorily employed.

15 Another object of the invention is to provide a printing mechanism, comprising individual hammers arranged for percussive action against printing type, equipped with a novel form of quick acting mechanism for controlling the operation of the hammers.

20 Another object of the invention is to equip an adding machine with type driving hammers arranged to be released under control of the type-carriers, provided with 25 equipment whereby the tripping elements of the hammers will not present any undue resistance against the type-carriers as the latter move to their positions in which the type on the carriers are supported in position for printing.

30 A further object is to provide a novel mechanism for interrupting or splitting the co-operative relationship between the hammers, whereby release of hammers in lower 35 numerical orders by hammers in higher numerical orders may be prevented.

In the drawings I have illustrated my invention embodied in a Dalton adding machine, though it will be apparent that the 40 use of the invention is not restricted to a Dalton machine. The invention may well be used in other embodiments. In the drawings,

45 Figure 1 is a side elevation of the operative mechanism of a Dalton adding machine having my invention embodied therein, certain of the shafts and frame parts being in section.

50 Fig. 2 is a plan view of the parts of the printing mechanism below the line A—A of Fig. 4.

Fig. 3 is a front elevation of the printing mechanism.

55 Fig. 4 is a side elevation of the printing mechanism, one of the side frame plates

being removed showing the hammers and the hammer latches engaged in their normal positions.

Fig. 5 is a similar view showing the positions of one of the hammers and its latch after the hammer has operated to print. 60

Fig. 6 is an enlarged plan view of the hammer latches and the co-operating couplings.

Fig. 7 is a view showing the construction 65 by which the couplings may be latched in different adjustments for the purpose of splitting the machine, or effecting co-operative relationship between the couplings in different numerical orders.

Fig. 8 is a view showing the coupling latched in position in which the co-operative relationship is interrupted so that the latch member on which said coupling is mounted may be released from its co-operating hammer without releasing the coupling in the adjacent lower numerical order. 70

Fig. 9 is an enlarged perspective view illustrating more clearly the arrangement 75 of the latches and couplings.

The mode of operation of the type-carriers 1 of the Dalton adding machines under control of the differential mechanism 2 is well known, as is the fact that the Dalton machine includes a controlling shaft 3 which 80 is turned in one direction to permit the type-carriers to operate after the differential mechanism has been set and is turned in the opposite direction to its starting point to return the type-carriers to their starting points after printing has been effected. 85

The usual adding pinions 4 and their controlling racks 5 are shown, said racks being co-operatively associated with the type-carriers in order to operate the adding pinions 90 properly. The printing type 6 are supported by the type-carriers and in the case of the Dalton adding machines are driven to effect printing upon paper fed to the type by a platen roller 7 and co-operating mechanism. 100

In the case of the Dalton machine the printing faces of the type are toward the platen and after the type-carriers have been operated to and stopped in proper positions to align the desired type at the printing line, 105 the hammers are percussively operated to strike the outer ends of the type and thereby drive the type as required to print.

My present invention comprises a set of printing hammers arranged in numerical 110

orders corresponding to the type-carriers, and novel mechanism for controlling the hammers in a novel mode of operation to effect printing. While it will hereinafter appear that the hammers are operated to drive the type to print after the shaft 3 has completed its turning movement in one direction and has started on its movement toward its starting point, I do not limit myself in this particular, except in the claims in which this feature is specially included, since the hammers may be caused to operate at other times if desired.

The printing hammers 8 are pivotally supported upon a shaft 9 and are guided between teeth of a comb plate 10 and also between the teeth of a comb plate 11. Each hammer is provided with a projecting arm 12 and retractile springs 13 connect the arms 12 with a rod 14, the power and tension of said springs being exerted to drive the hammers percussively against the type aligned at the printing line. For each hammer an individual releasable latch is provided, said latches being effective to hold the hammers in their retracted positions shown in Figs. 1 and 4 until said latches are released at the proper time by mechanism provided for that purpose. As shown, each latch comprises an appropriately shaped member 15 having a shoulder 16 for engaging the arm 12 of the corresponding hammer to hold the hammer retracted. Springs 17 connect depending arms on the latch members with a rod 18 and yieldingly hold the latches engaged with the arms 12 of the hammers. The latch members are operatively supported by the guiding comb plate 11 and another guiding comb plate 19 between the teeth of which comb plates the latch members are movable into and out of engagement with the arms 12 of the hammers. As will be apparent by reference to Figs. 4 and 5, the tendency of the springs 17 is to raise the rear or inner ends of the latch members from the positions shown in Fig. 4 to the positions shown in Fig. 5. When the machine is idle and at rest, the rear ends of the latch members 15 are held in their lower positions by appropriate projections 20 on the corresponding type-carriers (Fig. 1), said projections engaging the upper edges of the rear or inner ends of the latch members and holding them pressed downward. After printing has been effected the rear ends of the latch members are pressed downwardly to their normal or idle positions by projections 20 as the type-carriers move to their starting points. This is because the rear ends of the latch members 15 are in the path of movement of the projections 20 so that as the type-carriers return to their starting points the latch members are automatically returned to their proper positions.

A rod 21 is supported by the side frames of the hammer mechanism and serves as an abutment to limit rearward movement of the latch members and also as a species of fulcrum or pivot against which the latch members may turn when said members rise to the positions in which they are shown in Fig. 5.

Each of the latch members, except the one in the highest numerical order which is at the extreme left relative to the operator facing the machine, has a projection 22 extending toward the latch member in the adjacent higher order in position to be engaged by a coupling so that when any latch member above the one in lowest order is moved to release the corresponding hammer, all other latch members in lower orders may also be moved to release their hammers. Certain of the projections 22 are arranged to coöperate with pivoted couplings 23 which are preferably of resilient material supported on pivots 24 on adjacent latch members. Each coupling carries a block 25 which, in one position of the coupling, is in position to be engaged by the projection 22 on the latch member in the next adjacent lower numerical order; and which, in another position of the coupling, is out of position to be engaged by said projection, thus permitting the machine to be split or divided so as to prevent release of hammers in lower numerical orders as an incident to operation of hammers in higher numerical orders. As shown each coupling 23 is in the form of an angular plate supported on its pivot 24 near the angle of the coupling, and having a projection 26 serving as a detent to engage in an opening or recess 27 to latch each coupling in position to be engaged by the adjacent projection 22, and also arranged to be engaged in a recess 28 to latch the coupling in position so that it will not be engaged by the adjacent projection 22, thus leaving the latch member on which the coupling is supported free to be released without effecting release of latch members toward lower orders.

An extension 29 on each coupling serves as a key or handle by which the coupling may be engaged for purpose of adjustment to latch the coupling in either operative or inoperative position as desired. Since the operative mechanism of the machine is largely inclosed within a case provision is made for permitting access to the couplings through an opening 30 in the case.

Release of the hammers is effected at the proper time by a release bar 31 having one end pivoted on a support 32 (Fig. 2) and the opposite end pivoted to the upper extremity of a lever 33. The lever 33 is pivoted on a support 34 and the lower end of said lever has an arm carrying a roller 35 operating upon the upper edge of a cam 36 carried

- by the shaft 3 and having a depressed portion or recess 37 near its rear end. When the shaft 3 is turned in a forward direction, that is toward the operator of the machine, 5 the roller 35 rides upon the upper edge of the cam 36 and the printing hammers in the embodiment shown are not released until after the type-carriers have completed their movement toward printing position and 10 have stopped and become stationary. Just before the shaft 3 completes its forward turning movement, the roller 35 rides into the recess 37 and the upper end of the lever 33 moves rearwardly swinging the release 15 bar 31 with it. Such movement of the release bar 31 is sufficient to take said bar beyond the rear edges of the shoulders 38 on the latch members 15. The shoulders 38 had previously engaged against the under 20 edge of the release bar 31 and limited upward movement of the latch members which had been permitted to rise by the movement of the corresponding type-carriers to recording position. The type-carriers which had 25 not moved to the recording position remain stationary or approximately stationary and do not move a sufficient distance to permit the corresponding latch members 15 to rise. However, the latch members corresponding 30 to the type-carriers which had moved to recording position are permitted to rise, due to the fact that the projections 20 on the type-carriers which had moved to recording position permit such movement of the latch 35 members. From this it follows that the springs 17 raise the latch members which may be raised to engage the shoulders 38 of said latch members in front of the latch release bar 31 about the time that the shaft 40 3 completes its forward turning movement. As the shaft 3 starts on its return movement, that is its movement toward its starting point, the cam 36, by contact with the roller 35, swings the upper end of the lever 33 and 45 thereby the latch release bar 31 forwardly, thus moving forward to released position all of the latch members 15 whose shoulders 38 had become engaged in front of the release bar 31, as previously described. This operation occurs during the initial portion of 50 the return movement of the rock shaft toward its starting point in the embodiment shown; such release of the hammers being quickly effected, permitting immediate percussive action of the hammers against the type. The lever 33 is actuated in one direction by a spring 39 and is operated against the power of said spring by the cam 36.
- A device is provided to restore the hammers into latched engagement with the latch members 15. As shown, the restoring device comprises: a bail including a rod 40 supported transversely at the rear of the hammers by a pair of arms 41 which are 55 attached to a rock shaft 42. A lever 43,
- which may be an extension of one of the arms 41, or otherwise attached to the shaft 42, has a roller 44 operating on a cam 45 attached to the shaft 3. As the shaft 3 is turned in a forward direction to permit the 70 type-carriers to move to recording position, the cam 45 moves along under the roller 44 until a notch or depression 46 (Fig. 1) on the cam is presented at the roller. A spring 47 serves to actuate the arms 41 rearwardly 75 to swing the rod 40 away from the hammers to permit the hammers to be operated by their springs 13 when the hammers are released as above described.
- The movement of the bail away from the 80 hammers takes place about the time that the forward turning movement of the shaft 3 is completed and prior to the release of the hammers. When the shaft 3 starts on its return movement after having completed its 85 forward turning movement the cam 45 quickly raises the lever 43 thereby actuating the arms 41 and the rod 40 in a direction to restore the hammers into latched engagement with the latch members 15. 90
- From the foregoing it is apparent that my invention serves its purposes in a highly efficient manner. Plainly the invention may be used in adding machines other than the Dalton adding machine. I do not restrict 95 myself to the use of the invention in any particular machine, nor do I otherwise limit myself to unessential features since it is apparent that the invention may be varied without departure from the nature and principle thereof. 100
- What I claim and desire to secure by Letters Patent, is:—
1. In a recording machine, the combination of type-carriers, spring actuated hammers for driving the type on said type-carriers to print, a latch for holding each of said hammers in retracted position, a device for releasing the latches corresponding to the type-carriers in recording positions, springs for moving latches into latching engagement with said device when the corresponding type-carriers move to recording positions, and means controlled directly by the type-carriers preventing release of the 105 latches corresponding to the type-carriers which are out of recording position, and coöoperating with said springs to move released latches to their initial positions into engagement with the corresponding 110 hammers when the type-carriers move to their starting positions. 115
  2. In a recording machine, the combination of type-carriers movable to and from recording positions, hammers for driving the type on the type-carriers to print, means for retracting the hammers from the type, latch members for holding the hammers retracted, a device for releasing the latch members from the hammers corresponding 120 125 130

4
to the type-carriers in recording positions, a
spring for moving each of the latch mem-
bers into engagement with said device, and
means supported and operated by the type-
5 carriers for moving said latch members out
of engagement with said device as an inci-
dent to movement of the type-carriers to-
ward their starting positions, and arranged
10 to permit said springs to move said latch
members into engagement with the ham-
mers which had been operated.

3. In a recording machine, a shaft, ham-
mers pivoted on said shaft, elements for
guiding said hammers in their operations,
15 a latch member engaging each hammer, a
device for releasing said latch members
from said hammers, a trip actuated by one
latch member for releasing another latch
member from the hammer engaged by the
20 latter, means controlled by the type-car-
riers holding said latch members out of en-
gagement with said device when the type-
carriers are out of recording position and
permitting said latch members to be moved
25 into engagement with said device when the
type-carriers move to recording position,
and springs for moving said latch members
into engagement with said device when the
type-carriers move to recording position,
30 and for moving the latch members into en-
gagement with said hammers when the
type-carriers move from their recording
positions.

4. In a recording machine, the combina-
35 tion of a series of type-carriers, hammers
for driving the type on said type-carriers to
print, a rock shaft operable in forward and
return turning movements, mechanism for
positioning the type-carriers for printing
40 as an incident to the turning of said shaft
in one direction, latches holding said ham-
mers in retracted positions, a device actuated
by the return turning movements of
said rock shaft for releasing said latches
45 from said hammers during the return turn-
ing movement of said rock shaft, springs for
moving the latches into position to be en-
gaged by said device as an incident to move-
ment of the type-carriers to recording po-
50 sitions and arranged to move said latches
into engagement with the hammers as an
incident to movement of the type-carriers
from their recording positions and during
the return turning movement of said rock
55 shaft, and elements operated by the type-
carriers during their movement from re-
cording position for moving said latches
in opposition to the power of said springs
out of position to be engaged by said device,
60 and leaving said springs free to move said
latches into engagement with said hammers.

5. In a recording machine, the combina-
tion of a series of type-carriers, hammers
for driving the type on said type-carriers
65 to print, a rock shaft operable in forward

and return turning movements, mechanism
for positioning the type-carriers for print-
ing as an incident to the turning of said
shaft in one direction, latches holding said
hammers in retracted positions, a device for
70 releasing said latches from said hammers,
springs arranged to move said latches into
position to be engaged by said device as an
incident to movement of the corresponding
type-carriers to recording positions and ar-
75 ranged to move the latches into engagement
with the hammers as an incident to move-
ment of the type-carriers from their re-
cording positions, connections operated by
the rock shaft during the return turning
80 movement thereof to cause said releasing
device to release from the hammers such
latches as engage said device, and means op-
erated by the type-carriers during their
movement toward their starting points for
85 moving said latches in opposition to the
power of said springs out of position to be
engaged by said device, and arranged to
hold corresponding latches out of position to
be engaged by said device until the type-
carriers move toward their recording
90 positions.

6. In a recording machine, the combina-
95 tion of a rock shaft operable in forward and
return turning movements, type-carriers
movable to recording position during turn-
ing movement of said shaft in one direction,
spring actuated hammers for driving the
100 type on said type-carriers to print, a latch
member for engaging and holding each ham-
mer in a retracted position, a swinging bar
for releasing latch members during the ini-
tial movement of said rock shaft toward its
105 starting point after the type-carriers have
been positioned for printing, means for op-
erating said bar from said rock shaft during
the initial portion of the return turning
movement of said rock shaft, and a spring
110 connected with each latch member arranged
to move the same into position to be en-
gaged by said bar as an incident to move-
ment of the corresponding type-carrier
toward recording position, and arranged to
move said latch member into engagement
115 with the corresponding hammer as an in-
cident to movement of the corresponding
type-carrier from recording position.

7. In a recording machine, the combina-
120 tion of a rock shaft operable in forward
and return turning movements, type-carriers
movable to recording position during move-
ment of said shaft in one direction, ham-
mers for driving the type on said type-car-
125 riers to print, a latch member for engaging
and holding each hammer in retracted posi-
tion, a device for releasing said latch mem-
bers during initial movement of said rock
shaft toward its starting point after the
130 type-carriers have been positioned, springs
for moving said latch members during the

- forward turning movement of said rock shaft to position to be engaged by said device as an incident to movement of the corresponding type-carriers to recording positions and arranged to engage said latch members with their hammers as an incident to movement of the type-carriers from their recording positions and during the final operation of the return turning movement 5 of said rock shaft, and means operated by the type-carriers for disengaging said latch members from said device as an incident to movement of the type-carriers from recording positions, and permitting said springs 10 to engage the latch members with the hammers which had been operated.
8. In a recording machine, the combination of a rock shaft, type-carriers movable to recording position during turning movement of said shaft in one direction, spring actuated hammers for driving the type on said type-carriers to print, a latch member for engaging and holding each hammer in a retracted position, a device for releasing said 15 latch members during the initial movement of said rock shaft toward its starting point after the type-carriers have been positioned for printing, a cam on the rock shaft controlling and timing the operation of said device, means operated by the type-carriers for disengaging said latch members from said device, and means for operating said device from said rock shaft as an incident to movement of the type-carriers to their recording positions.
9. In a recording machine, a series of type driving hammers, a number of supports, a series of latches movable longitudinally on said supports into and out of latching engagement with said hammers, a bar, a stationary support to which said bar is pivoted, means for moving selected ones of said latches into position to be engaged by said bar, and a lever for oscillating said bar to release said latches from said hammers.
10. In a recording machine, a series of type driving hammers, a number of supports, a series of latches movable longitudinally on said supports into and out of latching engagement with said hammers, a bar, a stationary support to which said bar is pivoted, means for moving selected ones of said latches into position to be engaged by said bar, a lever for oscillating said bar to release said latches from said hammers, and devices for oscillating said lever.
11. In a recording machine, a series of type driving hammers, a number of supports, a series of latches movable longitudinally on said supports into and out of latching engagement with said hammers, a bar, a stationary support to which said bar is pivoted, means for moving selected ones of said latches into position to be engaged by said bar, a lever for oscillating said bar to
- release said latches from said hammers, and springs acting to move said latches into engagement with said hammers.
12. In a recording machine, a series of type driving hammers, a shaft on which said hammers are pivoted, springs for actuating said hammers in type driving operations, devices for guiding said hammers in their movements by said springs, a projection integral with each hammer, supports, latches 75 arranged for pivotal and longitudinal movements on said supports, a bar for moving said latches out of engagement with said projections, springs for moving said latches longitudinally on said supports into engagement with said projections and pivotally into engagement with said bar, a coupling member pivoted on each latch whereby latches in lower orders will be moved out of engagement with said projections by latches 80 in higher orders, and means for latching said couplings in position to prevent release of latches in lower orders by latches in higher orders, leaving the latches in higher orders free to be released while the latches 85 in lower orders remain engaged with said projections.
13. In a recording machine, a series of type driving hammers, a shaft on which said hammers are pivoted, springs for actuating 95 said hammers in type driving operations, devices for guiding said hammers in their movements by said springs, a projection integral with each hammer, supports, latches movable longitudinally on said supports 100 into and out of engagement with said projections, springs for moving said latches into engagement with said projections, a coupling member pivoted on each latch whereby latches in lower orders will be 105 moved out of engagement with said projections by latches in higher orders, means for latching said couplings in position to prevent release of latches in lower orders by latches in higher orders, leaving the latches 110 in higher orders free to be released while the latches in lower orders remain engaged with said projections, a pivoted release bar, and mechanism for operating said bar as required to release said latches.
14. In a recording machine, a number of type driving hammers, a shaft on which said hammers are pivoted, springs for operating said hammers, latch members for holding said hammers respectively in retracted positions in opposition to said springs, springs for holding said latches in engagement with said hammers, means for moving said latches in opposition to the last-named springs to release said latches 125 selectively, couplings pivoted to said latches, means for latching said couplings in position to effect release of latches in lower orders as an incident to release of latches in higher orders, means for latching said 130

couplings in position to permit operation of latches in higher orders without releasing latches in lower orders, and a manually engageable part wholly supported by each coupling whereby said couplings may be moved from one position to another.

15. In a recording machine, a series of type driving hammers, a series of latches for holding said hammers in retracted positions, 10 a bar for releasing said latches from said hammers, mechanism for moving said latches into and out of engagement with said bar, an angular coupling pivoted to one of said latches for releasing an adjacent latch as 15 an incident to release of the latch supporting said coupling, a projection on one arm of said coupling for engaging said latch to hold said coupling in position to effect release of the adjacent latch or out of position to effect such release of the adjacent latch as desired, and a manually engageable part supported by the other arm of said coupling for moving said coupling to said positions as desired.

25 16. In a recording machine, a series of type driving hammers, a series of latches for holding said hammers in retracted positions, a bar movable to release said latches from said hammers, a stationary support 30 upon which said bar is pivoted, a lever for oscillating said bar, a rock shaft, and a cam attached to said rock shaft arranged to operate said lever and thereby said bar in a direction to release said latches from said 35 hammers during the initial movement of said rock shaft toward its starting point after said rock shaft has completed its full movement from its starting point.

17. In a recording machine, a series of 40 type driving hammers, a series of latches for holding said hammers in retracted positions, a bar movable to release said latches from said hammers, a stationary support upon which said bar is pivoted, a lever for oscillating said bar, a rock shaft, a cam attached 45 to said rock shaft arranged to operate said lever and thereby said bar in a direction to release said latches from said hammers during the initial movement of said rock shaft 50 toward its starting point after said rock shaft has completed its full movement from its starting point, and mechanism operated by said rock shaft during movement of said rock shaft to its starting point after said 55 hammers have been released as aforesaid for operating said hammers to position to be engaged by said latches.

18. In a recording machine, a series of type driving hammers, a series of latches 60 for holding said hammers in retracted positions, a bar movable to release said latches from said hammers, a stationary support upon which said bar is pivoted, a lever for oscillating said bar, a rock shaft, a cam 65 attached to said rock shaft arranged to op-

erate said lever and thereby said bar in a direction to release said latches from said hammers during the initial movement of said rock shaft toward its starting point after said rock shaft has completed its full 70 movement from its starting point, and springs for operating the hammers which are released as aforesaid.

19. In a recording machine, a series of type driving hammers, latches for holding 75 said hammers retracted, a rock shaft arranged to be turned from and to a definite starting position, a device for releasing said latches from said hammers, a lever for operating said device, a cam operated by said 80 rock shaft arranged to operate said lever as required to cause said device to release latches during the initial movement of the rock shaft toward its starting position, after said rock shaft has completed its full 85 movement from its starting position, means for operating said hammers after they have been released, a bail for moving said hammers into latched engagement with said 90 latches after operation of said hammers as aforesaid, and a cam actuated by said rock shaft to operate said bail after said hammers have been operated and during movement of the rock shaft toward its starting position after that portion of the initial movement 95 of said rock shaft toward its starting position during which the hammers are released as aforesaid.

20. In a recording machine, a series of type-carriers movable to and from recording 100 positions, hammers for driving the type on said type-carriers to record, springs for operating said hammers, latches movable into and out of latched engagement with said hammers, a swinging bar, and means 105 movable by the type-carriers to position to hold said latches out of position to be engaged by said bar.

21. In a recording machine, a series of type-carriers movable to and from recording 110 positions, hammers for driving the type on said type-carriers to record, springs for operating said hammers, latches movable into and out of latched engagement with said hammers, a swinging bar, means movable by 115 the type-carriers to position to hold said latches out of position to be engaged by said bar, and means for moving into position to be engaged by said bar the latches which correspond to the type-carriers which are operated.

22. In a recording machine, a rock shaft operable in forward and return turning movements, a series of type-carriers movable to recording position during turning 125 movement of said rock shaft from its starting position, spring actuated hammers for driving the type on said type-carriers to print, latches for holding said hammers retracted, a device for releasing latches of the 130

hammers corresponding to the type-carriers which move to recording position, mechanism for operating said device to effect release of latches from hammers during the initial portion of the return turning movement of said rock shaft, and means on the type-carriers which remain stationary for preventing operation of latches holding the hammers corresponding to said stationary type-carriers.

23. In a recording machine, a rock shaft, type-carriers movable to recording position during turning movement of said rock shaft from its starting point, hammers corresponding to said type-carriers respectively, latches holding said hammers retracted, a swinging bar for releasing latches, means carried by the type-carriers for holding said latches out of position to be engaged by said bar, means 20 for moving the latches to position to be en-

gaged by said bar when the type-carriers operate, a cam operable by the rock shaft during the initial movement of said rock shaft toward its starting point after said rock shaft has completed its full movement from 25 its starting point for operating said bar to release the latches engaged by said bar, means for operating the hammers released as aforesaid, a bail for moving said hammers into latched engagement with said latch 30 members after operation of said hammers, and a cam operated by said rock shaft to operate said bail after said hammers have been operated as aforesaid and during movement of said rock shaft toward its starting point 35 subsequent to that initial movement of said rock shaft toward its starting point during which the hammers were released and operated.

HARRY LANDSIEDEL.
